G. M. KEEFAUVER.
COMBINED LEVEL AND GAGE.
APPLICATION FILED JUNE 5, 1915.

1,177,709.

Patented Apr. 4, 1916.

UNITED STATES PATENT OFFICE.

GEORGE MORRIS KEEFAUVER, OF FIATT, ILLINOIS.

COMBINED LEVEL AND GAGE.

1,177,709.

Specification of Letters Patent.

Patented Apr. 4, 1916.

Application filed June 5, 1915. Serial No. 32,302.

To all whom it may concern:

Be it known that I, GEORGE M. KEEFAUVER, residing at Fiatt, in the county of Fulton and State of Illinois, have invented 5 certain new and useful Improvements in Combined Levels and Gages, of which the following is a specification.

My present invention, which is in the nature of an improved tool or appliance designed for use in building forms for concrete 10 walks, driveways, feed floors, and also for placing "nailers" in building headers over doors and windows, more particularly has reference to improvements on the combined 15 level, and gage appliance shown in my Patent #1,074,367, issued September 30, 1913.

My present invention, which primarily has for its object to provide an improved 20 tool or appliance of the general purposes stated, that can be conveniently handled and adjusted to suit its requirements and which effectively serves its intended purposes, more 25 particularly has for its object to provide certain improvements on my patented combined level and gage above referred to that materially reduces the cost of manufacture, the number of parts and increases the general efficiency of the said patented gage and level.

30 Among other objects my present invention seeks to particularly provide for doubling the capacity of my patented appliance, in which the connection between the slide or extensible members is simplified and in 35 which the scale or indicator means is readable on both sides of the body of the implement.

With further objects in view that will hereinafter appear, my present invention 40 embodies the peculiar construction and novel arrangement of parts hereinafter described, specifically pointed out in the appended claims and illustrated in the accompanying drawing, in which:

45 Figure 1 is a perspective view of the invention, the same being shown in use in building a concrete walk. Fig. 2 is a longitudinal section of my improved combined level and gage, parts being in side elevation.

50 Fig. 3 is a transverse section of the same on the line 3—3 of Fig. 2. Fig. 4 is a perspective view of one of the extensible gage members. Fig. 5 is a detail perspective view of a portion of one end of the gage body and a 55 portion of one of the extensible members that co-operates therewith.

In my present form of combined level and gage, the body or stock 1 has the usual leveling bulb 2 and vertical or plumb bulbs 3 in the opposite ends thereof and metal plates 4—4 one on each end thereof, each of which is provided with a vertical slot 40 in the lower edge and which register with a groove 5 in the lower edge of the body 1 that extends the full length of the said body, as best 60 shown in Fig. 2.

In my patented level and gage appliance above referred to, the extensible or gage members are arranged in alinement, are T-shaped in cross section and are slidable endwise through the opposite ends of the body 1. By reason of the manner in which the extensible or gage members are connected with the body or stock 1, as shown in my patent mentioned, the extending capacity of the 70 said members is limited on account of their being approximately but one-half of the 75 length of the said body.

In my present invention, the extensible members 6—6 are approximately of the full 80 length of the body 1, are L-shaped in cross section, as is best shown in Fig. 3, by reference to which and to Fig. 2, it will be also noticed that the vertical flanges 60 of the member 6 are slidably mounted within the 85 groove 5 in the bottom of the body 1 upon each other while their flanges or bottom portions 61 each extend laterally in opposite directions to form bearing plates for riding over the under face of the said body 1, as 90 shown.

At the outer end 1 of the members 6 is a widened portion 62 which may be integral with or otherwise fixedly connected with the member 6 and each of the said widened portions 62 has a pendent lug 63 which lugs serve to locate the width portion for placing the side members or forms for the walk, as shown by Fig. 1.

7—7 designate strap hangers, one of which 100 is provided for engaging each of the slide members 6 and the said hangers fit in two sockets 8 in the body portion 1 that merge with the grooves 5 and with groove apertures 50 in the said body, the latter being 105 provided for receiving the clamping rods 9—9, the lower ends of which pivotally connect with the trap hangers 7—7 and whose upper ends are threaded for receiving the winged clamping nuts 16.

11 designates the carrying handle and 12 denotes indicator plates of which there is 110

one at each side of the body near the lower edge and which plates extend practically the full length of the said body.

An indicator finger 13 is secured to or formed on the inner end of each of the slide members 6 for traversing the indicator scale plates, as shown.

From the foregoing description taken in connection with the drawing, the complete 10 construction, the operation and advantages of my invention will be readily understood. By forming the extensible members 6 and mounting them on the body 1, as stated, the capacity of my patented gage and level before referred to is doubled. Furthermore, 15 by forming the body 1 with a single wide groove extending the full length of its bottom face and closing off the ends of the said groove by the metal end plates having a slot 20 wide enough for receiving the vertical flanges 60 of their coöperating members 6, suitable provision is made for holding the members 6 in proper position as they slide upon each other within the groove 5 during 25 the adjustment of the said members 6-6, the said slotted end plates also serving to guide the members as they are slid into and out of the body.

What I claim is:

30 1. A combined level and gage, comprising a body or stock having a bubble glass, a gaging means extensible at each end from the said body, said means including a pair of extensible members slidable upon each other, 35 the body having a groove in its bottom edge that extends the full length thereof and in which the slidable members are mounted, and means on each end of the stock or body for guiding their respective slide members,

the projected ends of the said slide members each having a gage lug and further means on the body for holding the slide members up in the groove of the said body. 40

2. A combined level and gage comprising a body or stock having a longitudinal groove 4 in its lower side that extends the full length thereof, a plate on each end of the body or stock each plate having a vertical slot that extends through the lower end thereof, and communicates with the groove in the stock, 50 a gage consisting of two members mounted flatwise against each other within the groove for endwise extension from the bcdy, each of said extension members being slidale through its respective slotted end plate, and provided with a pendent gage lug at the outer end, a hanger for each of the said gage members and means for suspending the hanger upon the body or stock. 55

3. A combined level or gage, comprising 60 a body or stock having a groove in its under side that extends the full length thereof, said body having the usual bubble glasses, a metal plate mounted on each end of the said stock, each plate having a slot that extends 65 through the lower edge thereof, a pair of gage members mounted in the groove to slide along each other, said members being slidale through the slotted end plates at their respective ends of the body, each gage member having a pendent gage lug, a hanger for each gage member, and means for removably mounting the hangers on the stock said means comprising a bolt pivotally connected to each hanger, that extends up through the 70 top of the stock and a draw nut engaging each bolt as set forth. 75

GEORGE MORRIS KEEFAUVER.
